UNITED STATES PATENT OFFICE.

LEONIE SOPHIA REYNARD, OF LONDON, ENGLAND.

WEARING-APPAREL, PARTICULARLY RELATING TO GOWNS, DRESSES, COATS, AND THE LIKE.

1,351,537.

Specification of Letters Patent. Patented Aug. 31, 1920.

Application filed September 29, 1919. Serial No. 327,076.

To all whom it may concern:

Be it known that I, LEONIE SOPHIA REYNARD, a subject of the King of Great Britain, residing at London, England, have invented 5 certain new and useful Improvements in Wearing-Apparel, Particularly Relating to Gowns, Dresses, Coats, and the like, of which the following is a specification.

The object of the present invention is the 10 production of a full length external garment as a gown, dress, or the like, for women's wear, which can be quickly and easily manufactured, can be applied to the wearer with great facility and effect, and which can 15 be constructed of any desired material or materials.

According to this invention and considered broadly, the garment is formed from one 20 piece of material, or it may be formed from differing materials joined together into one piece. Such a piece of material laid out flat or arranged in a single plane is then cut to shape; the general outline of the material when so cut is rectangular, of greater length 25 than breadth, and formed with an aperture about centrally of its length and about centrally of its breadth, through which aperture the head of the wearer is to be inserted, so that the material depends in front of and at 30 the back of the wearer.

On each side of the aperture the material is shaped as will be hereinafter more particularly specified, so that lateral portions overhang the wearer's shoulders; in front 35 of and at the rear of such overhanging portions the material is cut away to form curved recesses, and the back part of the material rearward of the aperture has two laterally extending tongues one upon each side, which 40 tongues are to be extended in length by additional portions of material added thereto by sewing or otherwise, although obviously such tongues might be cut from the same piece of material in cases where the forming 45 of the tongues in a piece with the main body would not be considered as an unnecessary use of a quantity of the said material.

The garment having been applied as afore- 50 said by the head of the wearer being passed through the aperture, so that the material depends in front of and at the back of the wearer, the two side edges of the hanging front portion are then drawn together at the back of the wearer underneath the hanging back portion and the said edges of the front

portion are secured together by suitable co-operating fastening devices. This having been done, the tongues extending from the loosely hanging back portion, which tongues together compose a kind of girdle or sash 60 are brought to the front of the wearer and loosely tied or otherwise secured, and a complete full length external garment is thus formed.

The garment will be further described 65 with reference to the accompanying drawing, which drawing shows a piece of fabric cut into the general form to constitute the garment according to this invention, although it is understood that the invention is not limited 70 to the identical outline thereby illustrated.

The aperture through which the wearer's head is to be passed is indicated at 1, the portion 2 forming the front part of the garment, while the portion 3 forms the back 75 part.

Forward of the aperture 1 and upon each side, the fabric is cut away at 4, 5, and similarly at a suitable distance rearward of the aperture 1 the garment is likewise cut 80 away on both sides at 6 and 7, the fabric laterally upon each side of the central aperture 1 extending at 8, 9 where it overlies the shoulders of the wearer, and 10, 11 are the tongues forming the girdle or sash. The 85 positions of fasteners at the edges of the front portion 2 are indicated at 12.

From the foregoing description it will be understood that with a garment so shaped the head of the wearer is passed through the 90 aperture 1, so that the lateral extensions 8, 9 overlie the shoulders and the part 2 then depends in front and the part 3 at the back of the wearer; the edges of the front part 2 are then secured together at the back of the 95 wearer beneath the part 3 which thus covers the connected edges and it is only necessary to then draw the ends of the sash 10, 11 to the front of the wearer and to secure the said ends together by tying or by other suitable means.

What I claim as my invention and desire to secure by Letters Patent is:—

1. A full length external garment for 105 women's wear comprising a piece of material, the general outline of which when laid out flat is rectangular and of greater length than breadth, said material having an approximately central aperture through which the wearer's head is to be passed to permit 110

said material to fall in front and at the rear of the wearer, the hanging front portion being of a width to permit its two side edges to meet together approximately centrally when drawn together at the back of the wearer underneath the hanging back portion, co-operating fastening devices to connect together the said meeting edges of the said hanging front portion and two laterally extending tongues rearward of said aperture one extending from each side of said material to form a girdle to be brought around and secured in front of the wearer.

2. A full length external garment for women's wear comprising a piece of material, the general outline of which when laid out flat is rectangular and of greater length than breadth, said material having an approximately central aperture through which the wearer's head is to be passed to permit said material to fall in front and at the rear

of the wearer, the hanging front portion being of a width to permit its two side edges to meet together approximately centrally when drawn together at the back of the wearer underneath the hanging back portion, co-operating fastening devices to connect together the said meeting edges of the said hanging front portion, and two laterally extending tongues rearward of said aperture one extending from each side of said material to form a girdle to be brought around and secured in front of the wearer, and curved recesses to pass under the arms of the wearer and lateral extensions to lie over the shoulders of the wearer.

In witness whereof I have hereunto set my hand in the presence of two witnesses.

LEONIE SOPHIA REYNARD.

Witnesses:

THOMAS W. ROGERS,
CYRIL GRIFFITH BREWER.
